UNITED STATES PATENT OFFICE.

JACOB BOBROW, OF BROOKLYN, NEW YORK, ASSIGNOR TO BOBROW OPTICAL MFG. CO., INC., OF BROOKLYN, NEW YORK, A CORPORATION OF NEW YORK.

DESIGN FOR A SPECTACLE FRAME.

Application filed November 2, 1925. Serial No. 15,324. Term of patent 7 years.

To all whom it may concern:

Be it known that I, JACOB BOBROW, a citizen of the United States, residing in the Borough of Brooklyn, county of Kings, city and State of New York, have invented a new, original, and ornamental Design for a Spectacle Frame, of which the following is a specification, reference being had to the accompanying drawing, forming a part hereof, in which—

Figure 1 is an elevational view looking at the front of the spectacle frame showing my new design; and

Figure 2 is a side elevation thereof.

I claim:

The ornamental design for the spectacle frame, as shown.

JACOB BOBROW.
